UNITED STATES PATENT OFFICE.

WILLIAM H. SANFORD AND HENRY BRICKHAM, OF DENVER, COLORADO.

PNEUMATIC THERMOMETER.

SPECIFICATION forming part of Letters Patent No. 643,542, dated February 13, 1900.

Application filed February 8, 1899. Serial No. 704,941. (No model.)

To all whom it may concern:

Be it known that we, WILLIAM H. SANFORD and HENRY BRICKHAM, citizens of the United States of America, residing at Denver, in the 5 county of Arapahoe and State of Colorado, have invented certain new and useful Improvements in Air-Thermometers; and we do declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

Our invention relates to improvements in thermometers; and the objects of our invention are, first, to provide a pneumatic thermometer; second, to provide a thermometer 20 that will visibly register the temperature of the apartment in which it is placed and will also register the temperature in which its actuating member is placed and also the temperature of the outside atmosphere and also 25 that in one or two or more compartments at a distance, and, third, to provide an air-thermometer adapted especially to school-houses, office-buildings, cold-storage plants, naval vessels, residences, &c., which will enable the 30 engineer or attendant in charge of the heating plant and also the superintendent or manager, if desired, to read the temperature of every room in the building from the engine-room and superintendent's office, so that the 35 engineer may know the temperature of every room without leaving the engine-room and can regulate the heating apparatus accordingly. We attain these objects by the mechanism illustrated in the accompanying drawings, in which—

Figure 1 is an elevation of the actuating member of our thermometer. Fig. 2 is a side elevation in section of Fig. 1. Fig. 3 is a front elevation of the temperature-indicator 45 of our thermometer, Figs. 1 and 3 and their connecting tube or conduit representing together the entire thermometer. Fig. 4 is a sectional side elevation of Fig. 3. Fig. 5 is a sectional plan view of the casing of Fig. 3 50 on line 5 of Fig. 4, but showing the interior mechanism in plan. Fig. 6 is a perspective

view of a portion of the temperature-indicator's actuating mechanism. Fig. 7 is a sectional plan view of Fig. 1 on line 7; and Fig. 8 is a sectional elevation of a building, illustrating the application of our thermometer to the different rooms and basement thereof.

Similar letters and figures of reference refer to similar parts throughout the several views.

Referring to Fig. 1, the numeral 1 designates an air-tight tank or closed can or air-tight receptacle of any suitable form or material. As illustrated it is of semicircular cross-section; but it may be of any suitable form. It is constructed of thin material, preferably metal, as brass, copper, or tin. This tank is made air-tight and has connected to it and entering it at any convenient point a tube or pipe 2. This pipe surrounds a nipple 3 and is secured to it or to the tank in any suitable manner. This pipe is preferably made of lead, although pipes of other metals can be used and also other materials, such as rubber. It may be of about an eighth of an inch internal diameter. Upon the face or 75 front of the tank we secure a thermometer 3^A, using one of any of the types of thermometers in use. The tank is sealed up perfectly air-tight, and in doing this a natural quantity of atmospheric air is imprisoned within it.

4 designates an indicating - register. It comprises a pear-shaped casing, in the narrow end of which is placed a corrugated flexible diaphragm 5, which is preferably made of metal, although any suitable material, as 85 rubber, may be employed. This diaphragm is attached to a raised ring 6, which projects above the back 7 of the tank. A nipple 8 projects from the back centrally of the diaphragm, to which the tube or pipe 2 is attached 90 and extends to the air-tank. Centrally from the top of the diaphragm a stem 9 projects upward, the top of which surrounds and holds a lever 10 at a predetermined distance from its opposite ends. This stem is supported by 95 a bracket 12^A, which is attached to the side of the casing. One end of this lever is provided with oppositely-extending trunions 11, which are pivotally supported in bearings formed in the ears 12 of the clip 13, which is 100 secured to the side of the casing. The opposite end of this lever is bifurcated and strad-

2
dles a spiral blade 14, that is formed on and makes a complete revolution on a shaft 15. This shaft is pivotally journaled at one end in the back of the casing and close to its opposite end to a bracket 16, which is secured to the back of the casing. The extreme end of the shaft adjacent to its bearing in the bracket extends through a suitably-indexed dial 17, which may be secured to the casing 5 in any convenient manner, and to its end a hand 18 is secured. The index on the dial is arranged to correspond to the graduation of the thermometer on the air-tank. Between the bifurcated end of the lever 10 and the stem of the diaphragm we attach one end of a spring 19, the opposite end of which rests on and is secured by solder or other means to a washer, which extends through an adjustable screw-plug 20, which is threadedly secured to an outwardly-projecting circular collar 21, formed on the back of the casing. This plug rotates freely on the stem 21^a of the washer, so that the plug can be turned without turning the washer and spring. A 10 set-screw 22 is threaded in the collar to bear on the screw-plug and secure it against accidental movement. This screw-plug is used to adjust the tension of the spring relative to the sensitiveness of the diaphragm to the action of the air and permits of the easy and accurate adjustment of the indicating mechanism of each thermometer.

The application and operation of our air-thermometer are as follows: The thermometer and gages are tested and adjusted to move in unison under varying temperature. Where the thermometer is to be applied to a building—say, for example, a school-house—the air-tanks are placed in the several rooms upon 15 brackets or on the walls in convenient places for occupants to read their thermometers. The registers are placed in the engineer's room 24 in the basement, and also when desired a set is placed in the superintendent's office 25. Each air-tank is connected by a pipe to a recording-gage in both places. Thus the pipe 26 of the air-tank 27 leads up through the partition against which it is placed to the floor-joists A above, along which it runs to the partition B and down along the studding to and through the floor C into the engine-room and to the gage 27. A branch pipe 28 also extends from the pipe 26 along the floor-joists A and into the superintendent's office to the gage 29. Air-tank 34 in room 35 is connected to gages 36 in engineer's office and gage 37 in the superintendent's office by the main pipe 38 and branch pipe 39. Air-tank 40 in room 41 is connected by pipes 42 and 43 to gages 44 and 45. Air-tank 46 in room E is connected by pipes 47 and 48 to gages 49 and 49. Air-tank 52 is connected by pipes 53 and 54 to gages 55 and 56, the main pipe running down through a recess in the brick. Air-tank 60 is placed on 60 the outside wall of the school-house and is connected by pipes 61 and 62 to gages 63 and 64,

which record the temperature of the atmosphere. 70 designates an air-tank in one of the halls 63, which connects only with a gage 71 in the engineer's room. As the gages register 70 alike and also tally with their respective thermometers, both engineer and superintendent know the temperature of every room in the building without running over the building to ascertain the temperature. They also know 75 the outside temperature, and the engineer can regulate the dampers of the heating apparatus to maintain a substantially even temperature throughout the building. As above stated, the tank and the pipe and also the diaphragm 80 contain air which is imprisoned in them when they are constructed and connected air-tight together. This imprisoned air is very sensitive and is increased in temperature and expanded in the tank by any perceptible increase in temperature in the air surrounding it, and the expansion in the tank is relatively in proportion to the increase of temperature of the atmosphere surrounding it. The air in the tank also cools and contracts as the surrounding atmosphere and the temperature cool. Now as the air in the tank heats and expands it forces the air in the tube and under the diaphragm against the diaphragm and raises the diaphragm and also the lever and 85 spring, and as the diaphragm rises it moves the lever up with it, which moves along the spiral blade and turns the shaft, and consequently the hand, around the index-dial. When the outside atmosphere is falling in 90 temperature, the air in the tank contracts and the spring draws the lever toward the back of the casing and along the spiral blade and turns the shaft and hand in the opposite direction. The imprisoned air responds so quickly to the 95 slightest variation in temperature that the least change is instantly indicated by the hand on the dial no matter how far apart the tank and gage may be. The laying of the fingers of the hand upon the tank will be instantly 100 detected by an upward movement of the dial-hand.

Our invention is very simple, durable, and reliable and will indicate the temperature of rooms or compartments at any reasonable distance from one or more central points, offices, or stations.

While we have illustrated and described a preferable mechanism for indicating the constantly-varying condition of the imprisoned 105 air relative to the surrounding atmosphere, we do not wish to be limited to it, as our invention contemplates the use of any indicating gage or apparatus that is adapted for the purpose. Consequently our invention contemplates, broadly, the imprisonment and confinement of air in any suitable air-tight tank, receptacle, casing, or apparatus and the connection thereto of an air-tight tube or pipe of any suitable material and of the laying of this 110 tube or pipe to any desired point inside or outside of a compartment in which the tank

is to be placed and in connecting it to any suitable temperature-indicating gage or apparatus.

We claim--

- 5 In a pneumatic thermometer, the combination of a temperature-indicating register comprising a casing, a graduated dial on said casing, an indicating-hand on said dial, a pivotal shaft supporting said hand, means for supporting said shaft, a spiral blade arranged to make substantially a full revolution of said shaft, and projecting from said shaft, a lever arranged to straddle said blade at one end, a pivotal support for the opposite end of said lever, an air-tight flexible undulating diaphragm in said casing, a stem projecting centrally from the center of the top of said diaphragm, means including a pivotal attachment between said stem and lever for oscillating said lever along said spiral blade by the

movements of said diaphragm, a contraction coiled spring secured at one end to said lever between said diaphragm and said spiral blade, a base-disk secured to the opposite end of said spring and pivotally attached to a thumb-screw plug, a threaded aperture in said casing to which said screw plug is threaded and means for securing said screw plug in adjusted position against accidental displacement, and with a pipe or tube connected to 30 said diaphragm and an air-imprisoning tank secured to the end of said tube, substantially as described.

In testimony whereof we affix our signatures in presence of two witnesses.

WILLIAM H. SANFORD.
HENRY BRICKHAM.
